[57] CLAIM

The ornamental design for a head and body pillow with pocket, as shown and described.

DESCRIPTION

FIG. 1 is a front elevational view of the head and body pillow with pocket of the present invention, the rear view being a mirror image thereof;

FIG. 2 is a left side elevational view of the head and body pillow with pocket of FIG. 1;

FIG. 3 is a right side elevational view of the head and body pillow with pocket of FIG. 1;

FIG. 4 is a top plan view of the head and body pillow with pocket of FIG. 1; and,

FIG. 5 is a bottom plan view of the head and body pillow with pocket of FIG. 1.
